THOMAS H. SYMINGTON, OF BALTIMORE, MARYLAND, ASSIGNOR TO T. H. SYMINGTON & SON, INC., OF BALTIMORE, MARYLAND, A CORPORATION OF MARYLAND

LATERAL MOTION MECHANISM

Application filed July 12, 1928. Serial No. 292,186.

The invention relates to railway car trucks, particularly to those of the type in which there is lateral motion of the truck bolster with respect to the side frames.

It is well known that many patents have been granted covering the provision of rollers mounted beneath the ends of the truck bolster for permitting lateral motion of the truck bolster to reduce the resistance to the passage of cars over curved track and to reduce lateral pressure and shocks between the wheel flanges and rails. There is a vast number of cars in operation equipped with these mountings popularly known as the Barber lateral motion devices. In such equipment which is now recognized as standard, the travel of the bolster in either direction is actually one inch and the lift, resulting from the coaction of curved surfaces with the lateral motion rollers, is three-sixteenths of an inch. The purpose in providing curved or inclined surfaces for coaction with the rollers and producing a lift is to effect return of the bolster to normal or intermediate position upon the cessation of the force tending to cause lateral motion in one direction or the other. As a matter of fact, experience has demonstrated that the standard lift above mentioned is insufficient to absorb the lateral forces without material shock on the side frames.

I have discovered that by increasing the lift of the truck bolster upon the occurrence of lateral motion the lift or upward thrust will be sufficient to absorb the lateral forces without shock to the side frames, thereby exercising a dampening effect on car roll such as results from synchronization of the periods of vibration of the truck springs with passage of the car wheels over rail joints.

It is with the above facts in view that I have devised the present invention which contemplates the provision of a lateral motion mounting or device of the general Barber type but arranged to increase the lift and also the travel of the bolster.

Another object of the invention is to provide a structure of this character in which the increased lift and travel may be obtained without increasing the angularity of the in-

clined surfaces coacting with the rollers beyond the maximum degree at which the rollers will roll instead of slipping.

Still another object of the invention is to provide a lateral motion device or structure of this type in which the surfaces coacting with the rollers are of such shape as to insure proper bearing at the normal or intermediate position and to insure a positive recentering after lateral motion occurs and the force tending to produce the same ceases.

A more specific object of the invention is to provide a lateral motion device located within the confines of the side frames and embodying rollers recessed into the underside of the bolster and operating upon a member supported directly upon the nest of truck springs.

The invention further contemplates the provision of differently shaped surfaces for coaction with the rollers all being of such form, however, as to produce the increased lift and travel.

An additional object is to provide a structure of this character which will be simple and inexpensive to manufacture and install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a view through a car truck longitudinally of the bolster, parts being in elevation and other parts being broken away and in section,

Figure 2 is a horizontal section through one side frame looking down upon the bolster, a portion of the latter being broken away to expose the lateral motion mounting,

Figure 3 is a diagrammatic view showing one shape for the surfaces coacting with the rollers,

Figure 4 is a similar view illustrating a different shape,

Figure 5 is a diagrammatic view disclosing still another shape for the surfaces,

Figure 6 is a diagram illustrating the difference between the work done with the 5 standard lift and travel and that performed in the present instance on account of the increased lift and travel.

Referring more particularly to the drawings, the numeral 1 designates the truck side 10 frames having the usual window openings 2 within which are located the reduced ends 3 of the truck bolster 4 which carries a center bearing 5 for the center plate 6 depending from the body bolster 7. The truck bolster 15 is represented as carrying conventional side bearings 8 with which coact depending bearing elements 9 carried by the body bolster. The center plate 6, body bolster 7 and bearing elements 9 form no part of the present 20 invention and hence are illustrated by means of dot and dash lines. Mounted within the window openings is the usual spring plank 10 upon the end portions of which are mounted the spring nests 11 which include caps 12. 25 The springs themselves are illustrated only diagrammatically at 13.

In accordance with my invention I provide a lateral motion device which comprises a seat member mounted on top of the spring nest and supporting rollers 14 which coact with bearing surfaces, to be described, on the bolster. The seat member, indicated generally at 15, comprises a body 16 formed as a casting and of a size somewhat greater than 35 the spring nest so as to fit thereover, there being a marginal flange 17 for preventing relative lateral displacement of the seat member and the spring nest, this flange extending outwardly of and entirely surrounding the 40 spring cap 12. The seat member 15 has its top formed with peculiarly shaped surfaces 18, and the underside of the bolster is formed with peculiarly shaped surfaces 19 for coaction with the rollers 14. It is possible that 45 these surfaces may be varied considerably insofar as exact shape is concerned and in Figures 3, 4 and 5 different alternate shapes are disclosed in detail as will be later described. The seat member 15 must necessarily 50 be prevented from any lateral movement with respect to the side frame and it is therefore represented as having laterally extending lugs 20 located outwardly or inwardly (or both) of the edges of the pedestal guides 55 as clearly indicated in Figure 2. By this particular arrangement it is clear that the seat member 15 may move vertically as the springs 13 are deflected but cannot move in any other direction whereas the truck bolster 4 may move laterally of the truck in either direction, the degree of movement being limited by outwardly extending stops 21 adapted to engage against the outer faces of the side frames at the pedestal guides or at 60 the edges of the window opening. In or-

dinary standard practice the stops 21 are so positioned as to permit a one inch movement of the truck bolster in either direction but in accordance with my invention the distance is increased so as to permit an actual movement of at least one and one-half inches, this having been discovered by actual experiment to be the most satisfactory to accomplish the desired results.

It might erroneously be supposed that to 75 accomplish the desired additional lift would require simply providing a steeper angularity or inclination in the surfaces which coact with the rollers. Such, however, would not suffice inasmuch as it is well known that if 80 the inclination of the surfaces which coact with the rollers be increased beyond a certain degree the rollers will not roll but will slip, thereby at least partially defeating the purpose of the structure. In the usual type 85 of Barber device three rollers are provided located so close together that there is little if any room to increase the travel at the safe angularity or inclination and thereby effect an increased lift. For this reason I 90 preferably, though not necessarily, employ two of the rollers 14 arranged considerably farther apart than those in the standard Barber device and preferably located substantially over the centers of the springs in 95 the nests. By spacing the rollers farther apart it is clear that there is sufficient distance between them to prolong the inclined surfaces to a sufficient extent to accomplish the desired additional lift without danger of 100 slipping of the rollers. When reference is made to "inclined" surfaces, this should be construed to mean "curved" surfaces or a combination of inclined and curved surfaces, as well, as these various possibilities are all 105 contemplated and are considered as well within the scope of the invention. By reducing the number of rollers it is possible to increase the diameter thereof materially beyond that of the well known type so that the 110 rolling action will be freer. On account of this increase in diameter and also on account of the necessity for maintaining the top of the bolster at the usual level, the rollers are disclosed as mounted partly within the bolster, the surfaces 19 thereof being upwardly offset with respect to the bottom edges of the bolster. Various mechanical details as to reinforcement, etc. may be provided as for example it is preferable to provide a longitudinal web 4^a within the bolster at the end portions thereof above and merging into the bottom walls which are formed with the surfaces 19.

As pointed out supra certain definite shapes 125 of surfaces may be used to advantage. In Figure 3 the surfaces 22 and 23 corresponding to the surfaces 18 and 19 are somewhat similar and the former is shown as comprising a portion extending between the points 130

24 formed as an arc of the same radius as the roller. This portion merges into other curved portions of greater radius extending between the points 24 and 25 and struck from the centers indicated. These second curved portions terminate at substantially the points where the usual surfaces in the Barber device would terminate and from these points these curved surfaces merge 5 into flat or plane inclined surfaces which are tangent thereto and which extend from the points 25 to the points 26. The surface 23 comprises a central curved portion extending between the points 27 and having a curvature greater than that of the roller. Actually, it is convenient that the arc forming this portion be formed by a radius equal to the diameter of the roller. This central curved portion merges into two less abruptly curved 10 portions extending from the points 27 to the points 28, the radius being materially greater than the diameter of the roller and the points 28 are located approximately where the usual surfaces in the Barber device would terminate and from these points these curved portions merge into flat or plane surfaces which are tangent thereto and which extend between the points 28 and 29. Under normal circumstances the rollers are located at their 15 central or intermediate positions between the surfaces 22 and 23 and as the curved portion of the surface 22 between the points 24 is coincident with the circumference of each roller it is apparent that there is at least a theoretical surface bearing of such shape that the rollers remain in their normal positions except upon the occurrence of a positive force tending to move the bolster laterally of the side frames. Furthermore, this 20 curvature will act to return the rollers to normal or central position after the cessation of the lateral motion producing force. The distance a between the points 24 and the distance a' between the points 27 may be the same though this is not necessary. The distance between the points 24 and 25 is indicated at b and the distance between the points 27 and 28 by b' . The distances a plus b or a' plus b' equals the travel in the ordinary 25 type of lateral motion device and the curvature of the surfaces is intended to be that which has been proved to be the maximum upon which rollers may roll without slipping. The distance c between the points 25 and 26 of the distance c' between the points 28 and 29 represents the increase in travel necessary to obtain the increased lift which is desired in accordance with the objects of this invention. In Figure 3 the normal position of the 30 roller is shown by a solid line while the positions at the end of the usual travel and at substantially the end of the increased travel are shown by broken lines.

In Figure 4 the top surfaces cooperating with the rollers are shown as identically the

same as in Figure 3 and the same reference characters are consequently employed. However, the bottom surfaces 30, taking the place of the bottom surfaces 18 or 22 are different so as to obtain two line bearings for each 70 of the rollers. The surface 30 is shown as comprising two similar curved portions extending from the central point 32 to points 33 struck from centers at opposite sides of the center line or axis of each roller when in 75 normal position and having a radius considerably greater than the diameter of the roller. On account of this formation each roller will contact with these curved surfaces at substantially the points 34, there being a slight 80 space, readily perceptible in Figure 4, between the periphery of the roller and the point where these surfaces intersect. The distances d between the center point 32 and the points 33 represent the total travel in 85 the ordinary type of lateral motion roller device. These curved surfaces merge into flat or plane but inclined surfaces which extend from the points 33 to the points 35, which surfaces are tangent to the curved surfaces 90 and which extend a distance e representing the increased travel necessary to obtain the additional lift desired. In view of the two-line contact resulting from the peculiar shape of the bottom surfaces 30 the rollers will also 95 tend to remain in neutral position prior to the occurrence of a positive force acting to effect lateral motion and by virtue of this arrangement the rollers will always return to such neutral position upon the cessation of a 100 force tending to produce lateral motion.

In Figure 5 there is shown still another modification in which the bottom surfaces 35 corresponding to the surfaces 18, 22 or 30 are not curved but are simply inclined from the center point 36 and made of such length that the increased travel for the desired increased lift will be had. In this instance there is again a two-line contact at the points 37 between the rollers and the surfaces 35 for centering purposes. The upper surfaces 38 corresponding to the surfaces 19 or 23 might of course be the same as illustrated in Figures 3 and 4 but are shown as including a flat land or central portion extending between the points 39 and from which lead inclined surfaces 40. The action in this instance is the same as that above described, the only difference being that the surfaces are not curved at any portion except at the ends where it is immaterial.

In connection with all the forms of the device, it is of course apparent that the roller moves only one-half its travel over the upper surface and one-half its travel over the lower 125 surface. In other words the roller moves one-half its travel on the relatively stationary lower surface while the relatively movable upper surface rolls one-half the travel on the roller. This is of course obvious to 130

one skilled in the art without further elaboration. Regardless of whether the coacting surfaces be formed as indicated in either Figure 3, 4 or 5 it is apparent that upon the occurrence of any force tending to move the car laterally with respect to the track, as for instance when passing around a curve or over a low spot in the rail, the body and truck bolsters may move as a unit laterally with respect to the truck, the curved or inclined surfaces moving with respect to the rollers 14. On account of the shape it is apparent that the bolsters and car body will be lifted with respect to the truck and side frames. This lifting force works against gravity and lateral thrust and there is consequently a neutralization of the opposing forces so that shocks to the side frames and other parts are absorbed and oscillation or rolling tendencies damped.

In Figure 6 I have shown diagrammatically the difference between the movement in a standard lateral motion roller device, such as the Barber type, and in the present device. Referring to this figure, the dimension *f* indicates the standard travel which is actually one inch, and the dimension *g* indicates the increase of at least one-half inch, obtained by my mechanism. The dimension *h* indicates the standard lift of three-sixteenths inch and *i* represents the increase in the lift, actually about five-sixteenths of inch. The curve between the points 41 and 42 indicates the curve of the existing lateral motion devices, and between the points 42 and 43 indicates the increase which is simply a straight line prolongation of the curve along the maximum safe angle. From a consideration of this figure it is apparent that the whole question involved is one of work done. Obviously the work done during movement of the bolsters for the increased distance and through the increased lift is greatly in excess of that accomplished by the ordinary arrangement.

From the foregoing description and a study of the drawings it will be apparent that I have thus provided a greatly improved lateral motion device which on account of the increase in travel and lift will possess characteristics and advantages not heretofore contemplated, particularly as there will be a complete elimination of the shocks incident to the standard design and a marked damping of any tendency of the car to develop a roll or side sway. It is really believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction

as will widen the field of utility and increase the adaptability of the device provided such changes constitute no departure from the spirit of the invention or the scope of the claims hereunto appended.

Having thus described the invention, I claim:

1. In a railway car truck, a lateral motion roller mechanism supporting the truck bolster for permitting movement thereof laterally of the side frames of the truck, and means for increasing the lift and travel as compared with accepted standards whereby to reduce the shock and effect damping of rolling tendencies of the car.

2. In a railway car truck including side frames, truck springs within the side frames, seat members engaged upon the springs and carrying rollers, and a truck bolster engaged upon the rollers, curved and inclined surfaces on the seat member and bolster coacting with the rollers to produce lifting of the bolster upon the occurrence of lateral motion in either direction, said lifting being to a greater extent than is accomplished by corresponding mechanism of accepted standard design.

3. In a railway car truck including side frames, truck springs within the side frames, seat members engaged upon the springs and carrying rollers, and a truck bolster engaged upon the rollers, curved and inclined surfaces on the seat member and bolster coacting with the rollers to produce lifting of the bolster upon the occurrence of lateral motion in either direction, said lifting being to a greater extent than is accomplished by corresponding mechanism of accepted standard design, said surfaces having inclinations of maximum degree capable of having rolling engagement with the rollers whereby to prevent slipping.

4. In a railway car truck including side frames, truck springs within the side frames, seat members engaged upon the springs and carrying rollers, and a truck bolster engaged upon the rollers, curved and inclined surfaces on the seat member and bolster coacting with the rollers to produce lifting of the bolster upon the occurrence of lateral motion in either direction, said lifting being to a greater extent than is accomplished by corresponding mechanism of accepted standard design, said surfaces being prolonged whereby the travel of the bolster will be increased beyond that of which standard designs are capable.

5. In a railway car truck including side frames, truck springs within the side frames, seat members engaged upon the springs and carrying rollers, and a truck bolster engaged upon the roller, curved and inclined surfaces on the seat member and bolster coacting with the rollers to produce lifting of the bolster upon the occurrence of lateral motion in either direction, said lifting being to a greater extent than is accomplished by corresponding

mechanism of accepted standard design, said surfaces having prolongations increasing the travel of the bolster, said surfaces being shaped to effect return of the bolster to normal central position upon the cessation of a force tending to produce lateral motion and having a plurality of line contacts with the rollers when the bolster is in normal or centered position.

5 10 6. In a railway car truck, a bolster, relatively stationary seats within the truck, seats on the underside of the bolster opposite the first named seats, and rollers interposed between the first and second named seats, certain of said seats having a formation providing a plurality of lines of contact with the associated roller when the roller is in intermediate position.

15 20 7. In a side bearing structure, opposed curved bearing surfaces and a roller interposed therebetween, one of said surfaces being formed to provide two lines of contact with the roller when the roller is in intermediate position.

25 30 8. In a side bearing structure, opposed curved bearing surfaces with a roller interposed therebetween, one of said bearing surfaces having bearing portions intersecting other than tangentially to define a plurality of lines of contact with the roller.

35 40 9. In a side bearing structure, opposed seats with a roller interposed therebetween, one of said seats having its central portion curved and struck from an arc having a radius substantially the same as the diameter of the roller and having other portions merging into said central portion and of curved form with a radius greater than the diameter of the roller struck from a point off center with respect to the axis of the roller in normal or intermediate position, and further having inclined portions merging into said second named curved portions.

45 In testimony whereof I affix my signature.
THOMAS H. SYMINGTON.
